INFLATABLE DILATOR

Leonard Greenburg, New York, N. Y.

Application April 9, 1948, Serial No. 20,024

16 Claims. (Cl. 128—4)

1

This invention relates to surgical accessories and to a method of surgery. More particularly, it relates to a surgical accessory for examining and enabling medical or surgical treatment of internal body organs or cavities, and also to a surgical method for gaining access to such organs or cavities.

In the practice of medicine and surgery it is often desirable to examine and treat various internal body cavities and organs such as the urinary bladder, lungs, stomach and rectum. Heretofore, in such operations, it has been the practice to insert a hollow metal tubular instrument into the internal organ or cavity through a canal or passage leading from the exterior of the body to such organ or cavity. During insertion of the instrument, the body canal through which it is passed is dilated and straightened, at least to some extent and after the instrument is fully inserted the interior of the organ or cavity may be examined and treated through the instrument. The use of such metal instruments causes considerable pain to the patient and there is the accompanying danger of injuring the passage tissues during insertion of the instrument. Other difficulties in operative techniques when utilizing such metal instruments are well known to the medical and surgical professions.

This invention provides a surgical accessory or instrument for examination and treatment of internal body organs or cavities and which may be inserted into the organ or cavity through an externally terminating body passage in a soft, flexible, non-rigid condition, but which, after insertion, may be straightened and made rigid to provide access through the instrument to the organ or cavity.

The invention further provides a surgical accessory of the type described which may be used with little or no pain to the patient and without danger of injuring the patient.

The invention also provides a new surgical technique or method of gaining access to internal body cavities or organs, which technique may be employed without causing pain to the patient and without injuring the patient.

A surgical accessory constructed in accordance with this invention comprises a double-walled, flexible, rubber tube, having one or more passages disposed between the two walls. The ends of the passages are hermetically closed, but the ends of the central bore of the tube are left open. A nipple or other suitable means, connected to the accessory and communicating with at least one of the closed passages in the double-walled portion, is provided for introducing fluid pressure into such passages, and means are provided in the

2

tube for establishing intercommunication between the passages. The portions of the tube between the passages structurally strengthen the accessory, also provide for uniform expansion and distension thereof, and prevent collapse of the inner wall upon introducing fluid pressure into the passages in the closed double-walled portion.

Several modifications of a surgical accessory constructed in accordance with this invention are shown in the accompanying drawing, in which:

Fig. 1 is an elevational view of the tubular surgical accessory;

Fig. 2 is an enlarged vertical sectional view taken along the line 2—2 of Fig. 1 and showing one modification of the accessory;

Fig. 3 is a transverse sectional view taken along the line 3—3 of Fig. 2;

Fig. 4 is an enlarged, vertical sectional view similar to Fig. 2, but showing a different modification;

Fig. 5 is a transverse sectional view taken along the line 5—5 of Fig. 4;

Fig. 6 is an enlarged vertical sectional view similar to Fig. 2, but showing another modification;

Fig. 7 is a transverse sectional view taken along the line 7—7 of Fig. 6; and

Fig. 8 is a transverse sectional view similar to Fig. 5 but showing a spiral arrangement of the ribs between the inner and outer tubes.

As shown in the drawings and particularly with reference to Fig. 2, the tubular accessory comprises an open ended, flexible, rubber tube 10, within the wall 11 of which one or more longitudinally extending passages 12 are formed, thus providing a double-walled structure. The passages are closed at one end 12a within the tube wall and terminate at the other end 12b in a header 13. The header may be formed integrally with the tube-wall or it may be formed in a separate unit and joined to the tube adjacent the ends 12b of the passages. A nipple 14 connected to one end of the tube communicates with header 13, and the other end of the tube-wall advantageously is tapered as shown at 11a to facilitate insertion of the accessory through the body passages or canals.

Instead of terminating in the header 13, the ends 12b of the passages 12 may terminate separately within the tube wall, in which event the nipple 14 communicates with one of the passages and small canals or apertures, such as shown in phantom at 15 in Fig. 3, extending through the portions of the tube wall between the passages, provide intercommunication between the pas-

sages. Such intercommunicating apertures may also be employed with the header arrangement shown in Fig. 2, if desired.

The modification of the invention shown in Figs. 4 and 5 comprises a flexible, rubber, outer tube 16 and an open-ended flexible, rubber, inner tube 17 of smaller diameter than tube 16. The inner tube is arranged within and spaced from the outer tube, thereby providing an annular passageway between the two tubes. The ends of the outer tube are hermetically closed upon the inner tube as by tapering or curving the insertion end portion 16a of the outer tube inward toward the inner tube and securing this end, as by means of vulcanization, rubber cement or the like, to the inner tube. The other end of the outer tube may be provided with an inwardly extending portion 16b which is hermetically joined as by vulcanization, rubber cement or the like, to the inner tube.

A plurality of spaced, longitudinally extending, web-like ribs 18 are disposed within the annular passageway between the inner and outer tubes and divide this passageway into a plurality of passages 19. The ribs 18 extend between and join the two tubes and may be formed integrally with both or one of the tubes as shown in Fig. 5, or they may be made separate from the two tubes and vulcanized or cemented to the tubes. A nipple 14 connected to the outer tube communicates with one of the passages 19, and several apertures or perforations 20 are provided in the ribs 18 for establishing intercommunication between the passages. The web-like ribs may extend substantially parallel to the axis of the tube as shown in Figs. 4 and 5, or they may be of other form (e. g. spiral as illustrated in Fig. 8).

In the modification shown in Figs. 6 and 7 the inner and outer tube type of construction is employed but the annular passageway between the tubes is filled with a sponge-like rubber mass 21 which is connected to the walls of the tubes. The mass 21 has a cell structure with intercommunicating interstices, and a portion of the annular passageway between the two tubes is left vacant so as to provide an annular header 22, with which the nipple 14 communicates. A header arrangement similar to that shown in Figs. 2 and 6 may also be utilized with the web-like rib structure shown in Figs. 4 and 5, in which event the apertures 20 may be eliminated.

To facilitate observation and inspection of internal body organs or cavities with this accessory, a small electric lamp may be located at or near the insertion end of the accessory and the wires for the lamp may be imbedded in the tube walls of the embodiments shown in Figs. 2 and 6, or they may extend through one of the passages 12 or 18, respectively, of the embodiments shown in Figs. 2 and 4, being imbedded within the insertion ends 11a, 16a, respectively, of these embodiments.

In any of the various modifications, one or more longitudinally extending partitions such as shown at 23 in Fig. 6 may be secured within the central bore of the tube to provide a plurality of open ended passages within the tube. The partition may be molded integrally with the tubular member or it may be made as a separate member and secured to the walls of the central bore of the tube by vulcanization, rubber cement or the like. With such arrangement, observation may be made through one of the bore passages while manipulation or treatment, including introduction and/or withdrawal of fluid is being accomplished

through the other passage or passages; or light may be passed through one of the bore passages while permitting observation and/or treatment through others.

5 In use, a surgical accessory constructed in accordance with this invention is usually inserted into the body cavity through the externally ending body passage while in a flexible, non-rigid or non-distended condition so that it can readily 10 follow the general shape or curvature of the passage or canal through which it is passed. However, if desired, the tube may be contracted during the insertion operation by applying suction to the closed passages between the inner and 15 outer walls of the tube. This is accomplished by connecting a source of suction or vacuum to the nipple 14. In some instances it may be desirable to distend the accessory somewhat, or to render it somewhat rigid, during the insertion 20 through the body passage. This may be accomplished by admitting a suitable amount of super-atmospheric fluid pressure into the passages between the inner and outer tubes.

In the normally non-distended condition or in 25 the above-described contracted or slightly distended conditions, the instrument has a high degree of flexibility and may be inserted through the body passage without causing pain to the patient. Inasmuch as the accessory is composed 30 of rubber or rubber-like material which is soft and flexible, it may be inserted through the body passage without danger of injuring the passage tissues. The inwardly tapered end portion permits the instrument to be inserted through the 35 body passage with minimum discomfort to the patient.

After the instrument has been positioned properly within the body passage so that its inner 40 end lies in the body cavity or organ which is to be examined or treated, fluid pressure is introduced into the passages between the inner and outer walls of the tube. Upon introducing a suitable amount of fluid pressure into the double-walled portion, the instrument will distend and 45 expand, thus making the instrument rigid and tending to straighten it within the body passage, thereby dilating the body passage and providing a substantially unobstructed passageway from the exterior of the body directly into the 50 body cavity or organ involved.

In some instances it may be desirable that the tube have a certain curvature while in the distended or rigid condition. This may be accomplished by moulding the tube in the desired shape, 55 by decreasing or increasing the size of the passages defined by the strengthening ribs at a particular location between the walls of the tube, by the use of less elastic rubber in one portion of the tube than in other portions, or by a combination of two or more of these procedures. The inner end of the central bore need not necessarily terminate in the end of tube, but instead may terminate in a side of the insertion end 60 portion of the accessory.

65 Although the accessory has been described as being made of rubber it is to be understood that other relatively soft, resilient, flexible materials such as synthetic plastics and the like may be utilized, and the use of the word "rubber" in the 70 claims includes such other material. Various other modifications in the arrangement of elements and in the details of construction of the accessory may be made without departing from 75 the spirit and scope of the invention.

I claim:

1. A surgical accessory for examining and treating internal body cavities, comprising a double-walled, flexible, open-ended, rubber tube having a plurality of passages extending substantially the entire length of the tube and disposed between the inner and outer walls, means hermetically closing the ends of the said passages, and means for introducing fluid pressure into said passages, thereby to subject the accessory to the effect of the fluid pressure confined within said passages.

2. A surgical accessory as defined in claim 1 in which the fluid pressure introducing means comprises a nipple attached to said tube near one end thereof, said nipple communicating directly with at least one of said passages.

3. A surgical accessory as defined in claim 2 in which the end portion of said tube opposite the end near which said nipple is attached is tapered inwardly toward the central bore of said tube.

4. A surgical accessory as defined in claim 1, including apertures extending through portions of said tube wall between adjacent pairs of said passages to provide intercommunication between said passages.

5. A surgical accessory for examining and treating internal body cavities, comprising a double-walled, flexible, open-ended rubber tube having a plurality of passages extending substantially the entire length of the tube and disposed between the inner and outer walls, means hermetically closing the ends of said passages, a common header communicating with said passages, and means for introducing fluid pressure into said header thereby to subject the accessory to the effect of the fluid pressure confined within said passages.

6. A surgical accessory for examining and treating internal body cavities, comprising a flexible, open-ended rubber tube having a plurality of longitudinally extending passages extending substantially the entire length of the tube and disposed within the tube walls, means hermetically closing the ends of said passages, and means for admitting fluid pressure into said passages, thereby to subject the accessory to the effect of the fluid pressure confined within the said passages.

7. A surgical accessory as defined in claim 6, in which said last-named means includes a common header communicating with said passages.

8. A surgical accessory as defined in claim 6, in which said last-named means includes apertures extending through portions of the tube-wall between adjacent pairs of said passages.

9. A surgical accessory for examining and treating internal body cavities, comprising a pair of flexible rubber tubes, one of which is disposed within and spaced from the other thereby providing an annular passageway between said tubes extending substantially the entire length thereof, means hermetically closing the ends of said passageway, web means disposed within said passageway and joining said tubes, and means for introducing fluid pressure into said passageway thereby to subject the accessory to the effect of the fluid pressure confined within said passageway.

10. A surgical accessory for examining and treating internal body cavities, comprising an outer flexible rubber tube, an inner flexible rubber tube arranged within and spaced from said outer tube thereby providing an annular pas-

sageway between said inner and outer tubes and extending substantially the entire length thereof, means hermetically closing the ends of said passageway, a plurality of web-like ribs disposed within said passageway and connecting said inner and outer tubes, thereby dividing said closed passageway into a plurality of passages, and means for introducing fluid pressure into said passages thereby to subject the accessory to the effect of the fluid pressure confined within said passages.

11. A surgical accessory as defined in claim 10, in which the fluid pressure introducing means comprises a nipple attached to said outer tube and communicating directly with at least one of said passages.

12. A surgical accessory as defined in claim 10, and including apertures in said web-like ribs providing intercommunication between said passages.

13. A surgical accessory as defined in claim 10, in which said ribs are arranged spirally within

in which said ribs are arranged spirally within said passageway.

14. A surgical accessory as defined in claim 10,
25 in which said ribs are arranged substantially longitudinally within said passageway.

15. A surgical accessory for examining and

15. A surgical accessory for examining and treating internal body cavities, comprising an outer flexible rubber tube, an inner flexible rubber tube arranged within and spaced from said outer tube thereby providing an annular passageway between said inner and outer tubes and extending substantially the entire length thereof, means hermetically closing the ends of said 30 passageway, a plurality of web-like ribs disposed within said passageway and connecting said inner and outer tubes, thereby dividing said 35 closed passageway into a plurality of passages, a common header communicating with said passages, and means for introducing fluid pressure 40 into said header thereby to subject the accessory to the effect of the fluid pressure confined within said passages.

16. A surgical accessory for examining and
45 treating internal body cavities, comprising an
outer flexible rubber tube and inner flexible rubber tube arranged within and spaced from said
outer tube, thereby providing an annular passageway between said inner and outer tubes ex-
tending substantially the entire length thereof,
50 means hermetically closing the ends of said passageway, a sponge-like rubber mass having inter-
communicating interstices disposed within said passageway and connecting said inner and outer tubes, and means for introducing fluid pressure
55 into the interstices of said sponge rubber mass thereby to subject the accessory to the effect of the fluid pressure confined within said inter-
stices.
